A. W. WARNER.
WATER SEAL FOR GAS RETORTS.
APPLICATION FILED NOV. 2, 1918.

1,423,975.

Patented July 25, 1922.

UNITED STATES PATENT OFFICE.

ARTHUR W. WARNER, OF MEDIA, PENNSYLVANIA, ASSIGNOR TO THE AMERICAN GAS COMPANY OF NEW JERSEY, OF CAMDEN, NEW JERSEY, A CORPORATION OF NEW JERSEY.

WATER SEAL FOR GAS RETORTS.

1,423,975.

Specification of Letters Patent. Patented July 25, 1922.

Application filed November 2, 1918. Serial No. 260,839.

To all whom it may concern:

Be it known that I, ARTHUR W. WARNER, a citizen of the United States of America, and resident of Media, in the county of 5 Delaware and State of Pennsylvania, have invented a certain new and useful Improvement in Water Seals for Gas Retorts, of which the following is a true and exact description, reference being had to the accompanying drawings, which form a part 10 thereof.

My invention relates to the manufacture of gas in retorts and has for its object to provide improved means for sealing the connection between the retort and its standpipe when it is desirable that this connection should be closed. A further object of my invention is to provide for the feeding of a 15 liquid into the lateral connection between 20 the retort and standpipe in a way well adapted for cooling the issuing gas and for rapidly filling the liquid seal which I use for closing the retort.

Heretofore valves of various forms have 25 been used for closing the lateral connection between retorts and standpipes, and have been found to give more or less trouble in use.

My invention, broadly speaking, consists 30 in providing water sealing mechanism in the lateral connecting the retort and standpipe, the shifting of a movable member of which will establish the water seal or allow it to 35 flow out and open the connection to the standpipe. The nature of my improvement will be best understood as described in connection with the drawing in which—

Figure 1 is a vertical section through a retort and standpipe showing also in section 40 my water trap and liquid feeding mechanism, and

Figure 2 is a cross sectional view on the line 2—2 of Figure 1.

A is the gas retort having a laterally extending conduit A', which should be downwardly inclined, and, as shown, is formed with a bottom portion A³ in the form of a segment of a cylinder, the top of this portion being indicated at A⁴. The lateral, in the 45 construction shown, is formed integral with the retort mouth piece and secured to the standpipe B by flanges A², the standpipe having a hole B' formed in its side in registration with the lateral.

50 In the illustrated construction side walls,

one of which is shown at A⁵, extend from the sides of the lateral conduit through the opening B', and are formed with inwardly projecting segmental flanges A⁶ having the same curvature as the bottom portion A³ of 60 the lateral.

C is a downwardly extending partition 65 extending from the top of the lateral to a point where its lower edge will come below the level of the liquid in the water seal when the sealing mechanism is in position to establish the seal. Obviously the top edge 70 B² of the opening through the standpipe will serve the same purpose if brought sufficiently low.

D is a shaft extending through the side of 75 the lateral conduit and actuated by an exterior handle (not shown). To this shaft is attached by arms E a dam E' having the form of a segment of a cylinder and adapted 80 to move in close proximity with the cylindrical bottom A³ of the lateral and the flanges A⁶. When the dam E' is retracted to the position shown in full lines any fluid 85 as well as gas from the retort will flow 80 freely from the lateral to the standpipe, and when swung forward to the position shown in dotted lines the dam and the bottom and sides of the lateral form a cup which will 90 retain any fluid, and with the partition C 95 form a water seal to prevent the flow of gas from the retort. Fluid for filling the water seal may be provided in any convenient way. In the construction shown fluid flowing down the standpipe will obviously be caught 100 and retained in the seal when the dam is operative, but I prefer to introduce liquid into the lateral conduit.

In the construction shown I form a slot 105 indicated at F across the top of the lateral to permit of a film of fluid being showered across the lateral in the path of the issuing gas and into the seal when the dam is raised. Above the slot F a box G is secured 110 having a chamber G' which is divided into a reservoir chamber G³ and an outlet chamber G⁴ by a dam G², which extends down into slot F, as shown, and is formed with depressed portions g² g³ at its top as shown in Fig. 2. An inlet port G⁵ leads into the reservoir chamber and is connected to the outlet port H' of a valve box H, having an inlet port H² connected to a fluid supply pipe J, and a seat H³ for a plug cock I having two ports I' and I² of different section,

which can be turned to register with the ports of the valve box, which box has also a waste outlet H^4 which can be connected with the port H^2 through an adjustment of 5 the plug cock.

In operation the smaller port I' is connected to the inlet and outlet ports and is adapted to furnish to and over the dam a sufficient supply of liquid to form a film 10 falling across the lateral to cool the issuing gas and maintain a flow of liquid over the retracted dam E' of the seal. The recessed portions g^2 of the dam edge insure that the liquid distribution shall be fairly equal 15 across the lateral. When it is desired to close a retort lateral the dam E' is turned up to operative position and by preference the cock turned to connect the larger port I^2 and thus fill the seal quickly.

20 The waste port H^4 is connected at times so as to show the operator that the ports I' or I^2 are clear and delivering their proper quantity of liquid.

Having now described my invention, what 25 I claim as new and desire to secure by Letters Patent, is:

1. In combination with a gas retort and a standpipe, a downwardly inclined lateral conduit connecting the retort with the stand- 30 pipe and so formed that liquids contained therein will flow freely into the standpipe, said conduit having a front wall extending down below the top of its rear wall and movable means operating to dam up liquid 35 in the lower end of the inclined conduit to a height above the bottom of its front wall.

2. In combination with a gas retort and a standpipe, a downwardly inclined lateral

conduit connecting the retort with the stand- 40 pipe and so formed that liquids contained therein will flow freely into the standpipe and a swinging cup-like dam pivoted in the conduit and fitting against the walls and bottom thereof, said dam being formed as described to permit a free gravitational flow of 45 liquid when restricted and to dam up the liquid to a desired height when swung outward.

3. A gas retort having a downwardly inclined lateral conduit leading from it in 50 combination with a standpipe into which said conduit opens at its lower end, a liquid supply conduit leading into the lateral conduit, a two-way cock having ports of different section for regulating the liquid 55 supply, and movable means for establishing and discharging a liquid seal in the lateral conduit.

4. A gas retort having a downwardly inclined lateral conduit leading from it in 60 combination with a standpipe into which said conduit opens at its lower end, a liquid reservoir located at the top of the lateral conduit and discharging into and across said conduit over a dam and means for feeding 65 said reservoir with liquid.

5. A gas retort having a downwardly inclined lateral conduit leading from it in combination with a standpipe into which said conduit opens at its lower end, a liquid reservoir located at the top of the lateral conduit and discharging into and across 70 said conduit over a dam having a series of depressed portions at its top, and means for feeding said reservoir with liquid.

ARTHUR W. WARNER.
